UNITED STATES PATENT OFFICE.

JOHN C. RINGE AND HENRY C. NISSEN, OF STRATFORD, CONNECTICUT, ASSIGNEES TO THE SINGER MANUFACTURING COMPANY, OF ELIZABETH, NEW JERSEY, A CORPORATION OF NEW JERSEY.

THREAD CONTROLLER FOR SEWING-MACHINE TAKE-UPS.

Application filed June 20, 1921. Serial No. 478,780.

To all whom it may concern:

Be it known that we, JOHN C. RINGE and HENRY C. NISSEN, citizens of the United States, residing at Stratford, in the county 5 of Fairfield and State of Connecticut, have invented certain new and useful Improvements in Thread Controllers for Sewing-Machine Take-Ups, of which the following is a specification, reference being had there- 10 in to the accompanying drawings.

This invention relates to improvements in thread-controlling devices particularly adapted for use with sewing machines employing rotary take-ups and is in the nature 15 of an improvement on the construction disclosed in the U. S. patent to O. B. Brush and S. Borton, No. 675,438, dated June 4, 1901.

The invention has primarily for its ob- 20 ject the provision of positively acting means serving to prevent continuous winding of the thread upon the rotary take-up of a sewing machine under the abnormal condi- 25 tion of the breaking of the thread between the take-up and the work.

To the attainment of the object of the in- 30 vention, the present improvement comprehends the provision of a thread-nipping or -holding device rendered effective to nip the thread between the thread-supply and the take-up upon the occasion of the break- 35 ing of the thread, between the take-up and the work, causing a winding of the broken thread upon the take-up. The act of nip- 40 ping the thread in this manner restrains the take-up from drawing thread from its sup- 45 ply, thereby breaking the thread between the thread-supply and the take-up, conse- quently preventing further winding of the thread upon the take-up. The broken thread already wound upon the take-up may then be readily pulled off from the take-up pins or studs, as only a few turns of the take-up, under this abnormal condition, 50 cause the second breaking of the thread in the manner described.

The thread-nipping device, in its pre- 55 ferred embodiment, is associated with the usual thread-guide adjacent the take-up and 60 comprises a stationary thread-nipping sur- face formed on the thread-guide block de- 65 tachably secured upon the head of the over- hanging bracket-arm of the sewing machine. Adapted to coact with this surface is a

movable thread-nipping surface provided 55 on a lever, pivotally sustained intermediate its ends upon the thread-guide block and over which lever the thread is led from the thread-guide to the take-up. During the 60 normal sewing operation, the angle of the thread leading from the thread-guide is such as not to cause any pressure upon the thread- 65 nipper lever, but should the thread start to wind upon the usual take-up studs, this angle is changed sufficiently to cause actua- 70 tion of the lever and a consequent nipping of the thread to restrain the take-up from further drawing thread from its supply.

In the accompanying drawings, Fig. 1 is a front end elevation, partly in section, of a 70 sewing machine embodying the present im- 75 provement and illustrating the change in angle of the lead of the thread to the take- up from normal to abnormal conditions. Fig. 2 is a top-plan view, partly in section, 75 of a portion of the overhanging arm of the sewing machine. Fig. 3 is a perspective view of the thread-guide block and attached thread-nipping device.

Referring to the drawings, the sewing 80 machine to which the present improvement has been applied is shown as constructed with a base 1 from which rises the vertical 85 standard 2 of the overhanging bracket-arm 3 terminating in the head 4. Suitably jour- naled in the overhanging bracket-arm is the rotary actuating shaft 5 carrying at its forward end the crank-disk 6 having the 90 crank-pin 7 connected in a well known man- 95 nner with the needle-bar 8 to impart vertical reciprocatory movements thereto in suitable 100 bearings provided in the head 4, the needle- bar 8 carrying the needle 9, as usual. Co- operating with the needle 9 in the formation 105 of lock-stitches is the rotary loop-taker 10 actuated in any suitable manner. The feed- 11 dog 11 adapted to at intervals project 110 through openings in the throat-plate 12 serves the usual function of feeding the work past the point of seam-formation, 100 while the presser-foot 13 opposed to the feed-dog is carried by the presser-bar 14 journaled for vertical movements in the 105 head 4 of the machine.

The rotary take-up embodied in this ma- 105 chine comprises disks 15 and 16 held in spaced relation by riveted studs 17 and 18. The portions of the studs 17, 18 interme-

diate the take-up disks are the effective elements of the take-up, acting in a well known manner either directly or by means of rollers carried thereby upon the thread leading 5 to the needle in the formation of stitches.

The take-up disk 15 is secured by means of screws, as 19 upon a boss 20, disposed concentric with the actuating shaft 5 and carried by a crank-arm 21 projecting from the

10 crank-pin 7. By means of this construction, each of the take-up studs 17 and 18 performs one rotation about the axis of the shaft 5 to each rotation of the latter, i. e., the paths of movement of the take-up 15 studs 17 and 18 are concentric circles.

Detachably secured to the head of the machine by means of screws, as 22, at a point closely adjacent the take-up disks, is a thread-guide block 23 formed or otherwise provided with oppositely projecting ears, as 24, having apertures, as 25, entered by the fastening screws 22. The block 23 is provided with a thread-guiding aperture 26 through which the thread T, drawn from 25 a thread-supply 27 through a tension device 28, is led in its passage to the take-up. A thread-nipping lever 29 is fulcrumed intermediate its ends upon the block 23 by means of a pivot-pin 30 secured in the block 30 by a set-screw 31. The rearward end of the lever 29 is provided with an offset lip 32 of a sufficient weight to normally hold this end of the lever depressed against a stop-pin 33 projecting from the block 23. 35 The inner surface of the lip 32 terminating in the edge 34 is adapted to coact with a corresponding surface 35 formed on the block 23 to, when from any cause the forward end of the lever 29 is depressed, positively grip the thread led over the edge 34 to the thread-aperture 26.

During the normal sewing operation, the angle of the thread emerging from the aperture 26 is never such as to exert sufficient 40 pressure upon the forward portion of the lever 29, over which the thread is led to the take-up, as to cause the rearward end of the lever to be raised sufficiently to nip the thread. In Fig. 1 is illustrated, in full lines, 45 substantially the position of the lowest angle of the thread when there is any pressure thereon by reason of the action of the take-up studs. It will be observed that the lead of the thread from the thread-aperture 26 50 is to the take-up 17, thence to the stud 18, thence to the needle, and that from the aperture 26 to the stud 17 the thread lies in a straight line, illustrating that there is no substantial pressure upon the front portion 55 of the lever 29. However, when the thread breaks between the take-up and the work during a sewing operation, the dangling end of thread is likely to wind about the two take-up studs 17 and 18, thereby 60 drawing the thread from its supply. At

the high speed of operation of the machine, it requires only a few seconds to jam a large quantity of thread between the two disks 15 and 16, i. e., the length of time required to stop the machine from the time the break 70 is first observed by the operator. This not only wastes a large quantity of thread, but consumes considerable time to remove the jammed thread.

According to the present construction, advantage is taken of the fact that when the thread starts to wind about the take-up studs, the lead of the thread from the aperture 26 changes from the stud 17 to the stud 18 as illustrated by the dotted lines 75 in Fig. 1. The change in angle of the lead of the thread is sufficient to positively depress the forward end of the lever 29, thereby raising the lip 32 to positively restrain movement of the thread through the aperture 26, consequently preventing further winding of the thread about the take-up studs. Further rotation of the take-up will thereupon break the thread between the take-up and the thread supply and after stopping 80 of the machine the few turns of thread wound about the take-up studs may be readily withdrawn therefrom. In case the thread breaks during the sewing operation at a point so close to the take-up as not 85 to leave a sufficient length of thread to start winding about the take-up studs, the present nipping device would not be thrown into action, but in that event there would be no occasion for its action. The present device 90 is therefore effective to prevent any substantial winding of thread about the take-up 95 studs.

The portion of the machine head 4 adjacent the guide-block 23 is cut away as at 100 36 to afford clearance for the lever 29, the forward end 37 of which latter is offset laterally so as to prevent the thread, looping outwardly beyond the take-up during the 105 sewing operation, from catching on the lever 29. The offset end 37 of this lever therefore 110 serves as a guard. A feature of this device is that it may be readily applied to machines in use without altering the timing of the operative parts of the machine.

Having thus set forth the nature of the invention, what we claim herein is—

1. In a sewing machine, the combination with a rotary take-up and a thread-supply, of means for preventing the drawing of thread from its supply under an abnormal condition of the winding of the thread upon the take-up, said means including relatively movable elements rendered effective by the action of the thread.

2. In a sewing machine, the combination with a rotary take-up and a thread-supply, of a thread-nipping device located on the thread-supply side of the take-up and normally ineffective to grip the thread acted 120 125 130

upon by said take-up, and means controlled by the thread for operating the thread-nipper to cause breakage of the thread under the abnormal condition of the winding of the thread about the take-up.

5. In a sewing machine, the combination with a rotary take-up and a thread-supply, of relatively movable elements located on the thread-supply side of the take-up, and 10 an arm connected with one of said elements, said arm being constructed and arranged to normally lie closely adjacent to the thread leading to the take-up, and acted upon by said thread to actuate the element connected thereto to prevent drawing of thread from 15 its supply under an abnormal condition of the winding of the thread upon said take-up.
4. In a sewing machine, the combination 20 with a rotary take-up and a thread-supply, of a thread-guide for directing the thread to said take-up, a lever pivotally supported adjacent said thread-guide, a stationary thread-nipping surface, and a thread-nipping surface provided on said lever for co-

action with said stationary surface, said lever having a portion positioned to be acted upon by the thread under an abnormal condition of the winding of the thread upon the take-up.

- 30 5. In a sewing machine, the combination with a rotary take-up and a thread-supply, of a thread-nipping lever rendered effective to prevent drawing thread from its supply by an abnormal action of the thread to wind upon said take-up, a pivotal support for said lever, and a guard for preventing the thread from catching on said lever during the 35 normal sewing operation.

6. A thread-nipper for sewing machines 40 comprising relatively movable elements effective for nipping the sewing thread therebetween, and means for rendering said thread-nipper effective by an abnormal lead of the thread occurring during the normal 45 operation of the machine.

In testimony whereof, we have signed our names to this specification.

JOHN C. RINGE.
HENRY C. NISSEN.
